Application September 17, 1949, Serial No. 116,396

14 Claims. (Cl. 53—26)

1

The present apparatus relates to control apparatus for automatic wrapping machines.

Various problems are presented in the control of packaging machinery and these problems have been solved in various ways and with varying degrees of success. When using transparent wrapping material, marks on the material have been used for actuating the control apparatus for the wrapping operation but this has not been fully successful due to the frequent lack of exact registry of the article to be wrapped with the marks and further due to variations in the size of the articles to be wrapped. These and other problems are solved by the present apparatus which controls the wrapping equipment as a function of the location and size of the article itself without regard to the markings on the wrapping material.

It is thus a principal object of this invention to provide improved control apparatus for wrapping machines.

It is a further object to provide control apparatus which operates as a function of the size and location of the article to be wrapped.

It is also an object to provide wrapping control apparatus wherein the leading edge of an article initiates the wrapping operation and the trailing edge of the articles normally controls subsequent operations.

It is an additional object to provide control apparatus having a "memory" sufficient to avoid the too soon repeating of an operation.

It is a further object to provide control apparatus wherein the sensing devices are spaced by an amount equal to the desired minimum spacing of the article to be wrapped on the conveyor.

It is another object to provide packing control apparatus which anticipates the movement of the article to be packaged.

It is also an object to provide improved packing control apparatus wherein the leading edges of a series of articles controls the apparatus.

These and other objects will become apparent upon a study of the following specification and drawings wherein:

Figure 1 is a schematic view of the present apparatus.

Figure 2 is a modified schematic view of the control apparatus which may be used with the conveyor of Figure 1.

The present apparatus is used to control a packaging machine such as that schematically shown in Figure 1 and comprising a continuous belt 10 running over a pair of spaced idler pulleys

2

11 and 12. A pulley 13 driven by motor 14 is located slightly below the normal alignment of the upper portion of belt 10 so that it is free to turn without engaging the belt when the belt is in a normal or unbiased condition, but a weighted wheel or pulley 15 is located directly above pulley 13 and normally presses against belt 10 to force it into engagement with pulley 13 so that the belt 10 may be driven thereby. Weighted wheel or pulley 15 engages the belt 10 by its own weight and may be retracted by energization of a solenoid comprising winding 16 and core member 17, core 17 being attracted into an upper position by winding 16 when said winding is energized, thereby lifting wheel 15 from the belt 10 and permitting the belt 10 to rise slightly above pulley 13 and cease to be driven thereby.

The wrapping material used is a transparent material 22 such as cellophane supplied from a reel 19 and trained over idler and tensioning pulleys 20 and 21 and extends along and is carried by the upper portion of belt 10. After leaving idler pulley 21, material 22 passes by upwardly extending guide members 23 which serve to turn the edges of the material upwardly to form, in effect, a trough or channel-like section of the wrapping material, this trough or channel-like form being carried through the major length of the belt. Wrapping material 22 has advertising matter and guide marks printed thereon and workers disposed along the belt, not shown, deposit the articles to be wrapped upon the moving wrapping material, using the marks and advertising as locating indicia. Near the right end of the belt, a series of progressively turned over guide members 25 further fold the edges of the wrapping material over and lap them, these folding guides being followed by a heated sealer wheel 26 which bears down on the moving lapped edges to thereby seal them together by heat and pressure. Subsequent to passing under the sealer wheel, which thereby forms a continuous tube carrying the spaced articles, the tube then runs beneath wheel 15 and shortly thereafter is deposited by belt 10 on cutting and sealing table 28.

Table 28 has a cutting slot 29 formed between two metallic members 30 and 31 extending across the table. An elongated cutter and sealer member 32 is electrically heated and is arranged to contact with members 30 and 31 to cut the cellophane tube when member 32 is moved downwardly and to heat and seal the adjacent edges of the cellophane tube. Cutter and sealer 32 is normally held in a retracted position by spring 33 and is

urged downwardly by a solenoid including a winding 34 and a core member 35, core member 35 being pulled downwardly by coil 34 when said coil is energized, thus causing a cutting and sealing operation of the adjacent edges of the tube 5 each time that coil 34 is energized.

A first slot 37, is cut through and extends a short distance across table 28, slot 37 being arranged a predetermined distance forward of slot 29 and is adapted to be covered by the articles 10 contained in the tube of wrapping material as they pass through. A second and similar slot 38 is arranged on the other side of slot 29. Suitable illuminating means or lights 39 are arranged directly above slots 37 and 38 and photocells of other light sensitive devices 41 and 42 are located beneath said slots 37 and 38, respectively, so that light shining through said slots will fall upon said photocells or like devices. Photocell 41 is connected in controlling relation to amplifier 43 and photocell 42 is connected to control amplifier 44. Amplifiers 43 and 44 are energized from line wires 87 and 88 by the circuits shown and may be of any conventional sort capable of controlling a relay as its respective photocell is subjected to or is cut off from the light source.

Amplifier 43 is connected to control the energization of winding 46 of relay 47 and relay 44 is connected to control the energization of winding 48 of relay 49. Relay 47 also includes switch blades 51 and 52, blade 51 being engageable with "in" contact 53 and blade 52 being engageable with "out" contact 54. Likewise, relay 49 includes switch blades 57 and 58 engageable with "in" contacts 59 and 60, respectively. Relay 49, in addition to other functions, controls relay 62 which includes winding 63 and blades 64, 65 and 66 engageable with "in" contact 61, "out" contact 68 and "in" contact 69, respectively. These relays assist in controlling a load relay or a contactor 40 having a winding 72 and a switch blade 13 engageable with "in" contact 14.

Also assisting the above relays in controlling contactor 11 is an electronic timer 75, said timer including an electronic discharge device 76 having a winding 77 of plate relay 78 in its plate circuit, said plate relay also including a switch blade 79 engageable with contact 80. The plate circuit of discharge device 76 is energized by secondary winding 82 of transformer 83, primary winding 84 of this transformer being connected by wires 85 and 86 to line wires 87 and 88, respectively. A direct current network is formed by secondary winding 90 of transformer 83 connected through discharge device 91, resistor 92, resistor 93, resistor 94 and wires 95 and 96 back to secondary winding 90. The control grid and cathode of device 91 are connected together so that this device acts as a rectifier and, while 91 is shown as a separate device, it may be part of a dual triode, device 76 being the other part of the device. With the arrangement shown, it may be assumed that the upper end of resistor 94 will be maintained positive and the lower end of resistor 93 will be maintained negative by the D. C. source described. A filter condenser 97 is connected across this D. C. network and a tap between resistors 93 and 94 is connected to the cathode of device 76 and to ground. The control grid of device 76 is connected through a charging condenser 98 to the upper end of resistor 94 and a rheostat 99 is connected in parallel with this condenser. The negative side of the above D. C. network is connected to the control grid by a circuit starting from the bottom of resistor 93 and including 70

rheostat 101, wire 102, terminal 103, wire 104, contact 53, blade 51, wire 105, contact 67, blade 64, wire 106, terminal 107 and wire 108 which connects to the control grid of the device 76. The plate relay 78 of timer 75 controls a load relay 111 having a winding 112 and a switch blade 113 engageable with "out" contact 114 and "in" contact 115, contact 115 being connected to terminal 116. Contact 114 is connected to terminal 117 and blade 113 is connected to terminal 118.

A second timer 120 is similar to timer 75, with terminals 121 and 122 corresponding to terminals 103 and 107, and terminals 123, 124 and 125 corresponding to terminals 116, 117 and 118, respectively. A third timer 130 is essentially the same as timer 75 and has terminals 131, 132, 133, 134 and 135 corresponding to 103, 107, 116, 117 and 118, respectively. This timer differs slightly from 75 by having terminals 133 and 135 connected by a wire 136. Switch blade 137 of timer 130 corresponds to blade 113 of timer 75 and blade 138 of timer 120 also corresponds to 113. Timer 130 is connected to line wires 87 and 88 by wires 140 and 141 and timer 120 is connected to the line wires 87 and 88 by wires 142 and 178 and 143, respectively. To more fully explain the present apparatus, its function will now be described.

Operation

With line wires 87 and 88 connected to a suitable source of current, and with motor 14 energized by a circuit: line wire 87, wire 150, wire 151, wire 152, motor 14, wire 153, wire 154 and wire 155 to line wire 188, said motor is energized and rotating pulley 13. Amplifier 43 is energized by the circuit: line wire 87, wire 150, wire 151, wire 181, amplifier 43, wire 182, wire 154, wire 155 and line wire 88. Amplifier 44 is connected to line wires 87 and 88 by wires 183 and 184, respectively, and cutter and sealer 32 are energized by the circuit: line wire 87, wire 185, cutter and sealer 32, wire 186 and wire 176 to line wire 88. Because relay 71 is open, and weighted wheel 15 is pressing belt 10 against pulley 13, the upper portion of belt 10 is moving to the right and carrying along the cellophane wrapping material 22 and one of a series of articles 156 is approaching slot 37. As light 39 is able to freely shine through the wrapping material 22 and into photocell 41, it being assumed that the marks and advertising matter on the cellophane are unable to cut off the light, the photocell is energized and amplifier 43 is operative to energize winding 46, thereby pulling in relay blades 51 and 52. Also, photocell 42 is exposed to light 39, hence amplifier 44 is energizing winding 48 of relay 49 to pull in switch blades 57 and 58. With the relay 49 pulled in, relay 62 is also pulled in by a circuit: line wire 87, wire 158, winding 63, wire 159, switch blade 58, contact 60, and wire 468 to line wire 88. With both photocells energized as above described and their respective relays pulled in, the D. C. charging circuit of timer 75 is completed from terminal 103 through wire 104, contact 53, switch blade 51, wire 105, contact 67, switch blade 64 and wire 106 to terminal 107. With this circuit completed, and with the potential at the lower end of resistor 93 being negative, the upper side of charging capacitor 98 is charged rather highly negative, the control electrode is negative and the discharge device 76 is nonconducting, hence relay 78 is not energized sufficiently to pull in its switch blade 79. As a consequence, relay 116 is also not energized and switch blade 113 is in engagement with its "out" contact 114. Timer 130

is likewise controlled so that its switch blade 137 engages the "out" contact connected to terminal 134 because its terminals 131 and 132 are connected by a circuit completed by wire 161 extending from terminal 131 to switch blade 66, "in" contact 69, and wire 162 back to terminal 132. Terminal 121 of timer 120 is connected by wire 163 to "out" contact 68 of relay 62 and terminal 122 is connected by wire 164 to switch blade 65 engageable with "out" contact 68 when relay 62 is deenergized but, as relay 62 is pulled in, the D. C. charging circuit for timer 120 is open, its discharge device is conducting and its relay blade 138 is pulled in. Winding 72 of load relay 71 is connected by wires 155 and 165 to line wire 88 and by wires 172 and 166 to contact 59 of relay 49 thence through switch blade 57 and wire 167 to terminal 124 of timer 120. However, switch blade 138 has been pulled in, as above mentioned, hence winding 72 is not energized by this circuit. A parallel circuit for winding 72 extends from wire 172 through wire 168, switch blade 52, contact 54, wire 169, terminal 136 of timer 130, switch blade 137 of said timer, wire 136, terminal 133, wire 170, terminal 117, switch blade 113, terminal 118, and wire 171 to line wire 87, but this circuit is open because relay 47 is energized and blade 52 is out of engagement with its "out" contact 54. Thus, there is nothing to prevent the continued movement of the upper portion of belt 10 to the right.

When article 156 passes over slot 37 and interrupts the light from bulb 39 to photocell 41, photocell 41 becomes non-conductive, relay 47 is deenergized and blade 51 disengages contact 53 and blade 52 engages contact 54. When this happens, relay 71 is energized by the circuit previously traced from line wire 88 including switch blade 52 and contact 54 and through timers 130 and 75. With winding 72 of relay 71 energized, blade 73 is pulled into engagement with contact 74 and solenoid windings 16 and 34 are energized by the circuit: line wire 87, wire 173, blade 73, contact 74, wire 174, winding 16, wire 175, winding 34, and wire 176 to line wire 88. Obviously, windings 16 and 34 may be connected in parallel instead of series, if desired. Energizing winding 16 attracts armature 17 of the solenoid upwardly and thereby lifts weighted pulley 16 off the belt 10 and permits said belt to spring slightly above pulley 13, thereby disrupting the driving relation between pulley 13 and the belt. This causes the belt and wrapping material to stop and, at the same time, the energization of winding 34 causes armature 35 to be attracted to a lower position thereby driving cutter and sealer 32 downwardly to cut the cellophane material and eject the cut portion through slot 29 and at the same time seal both edges of the cut by heat and pressure.

The same operation of relay 47 that caused the energization of relay 71 also opened the afore-mentioned charging circuit for timer 75 and thus permits the negative charge on the control electrode to be dissipated. As the negative charge leaves timing condenser 98 through rheostat 99 and the wire 177 to wire 195, the control electrode tends to become positive relative to the cathode so that the device 76 becomes conductive to the extent that relay 78 pulls in its switch blade 79 with the result that relay 111 is energized and pulls switch blade 113 out of engagement with "out" contact 114. This breaks the afore-described energizing circuit for relay 71, hence the relay contacts open and deenergize

coils 16 and 34. This permits the cutter and sealer 32 to be lifted to the position shown by spring 33 and also permits wheel 15 to reengage the belt 10 with its driving pulley 13 to cause further forward motion of the belt and its cellophane tube containing the articles 156 to be wrapped. As the afore-mentioned article 156 passes over slot 37, photocell 41 remains non-conductive, hence relay 47 remains deenergized. With slot 38 still not covered, relays 49 and 62 are energized and, as a result, timer 130 continues with switch blade 137 in an "out" portion and timer 120 continues to hold blade 138 in.

Upon said article 156 covering slot 38 and thereby interrupting the light from bulb 39 to photocell 42, amplifier 44 drops out relay 49 and thereby drops out relay 62, and thus opens a portion of one of the energizing circuits for winding 72 of relay 71 previously described. The deenergization of relay 62 causes switch blade 65 to engage "out" contact 68 and thereby completes the D. C. charging circuit for timer 120 which extends from terminal 121 through wire 163, contact 68, switch blade 65 and wire 164 to terminal 122. Upon a sufficient negative charge being built up in the charging condenser of timer 120, the tube becomes nonconductive and its relays are dropped out with a result that blade 138 engages the contact connected to terminal 124. The deenergizing of relay 62 causes the control circuit of timer 130 extending from terminal 131 through wire 161, blade 66, contact 69 and wire 162 to terminal 132 to open, thereby permitting the negative charge to leak off its timing condenser and its tube to be rendered conductive with the result that switch blade 137 is pulled in. Thus, with article 156 covering both slots 37 and 38, timer 75 pulls in its relays, timer 120 drops out its relays and timer 130 pulls in its relays. As no energizing circuit for relay 71 is complete, solenoid windings 16 and 34 remain deenergized and belt 10 continues in operation. Upon article 156 clearing the slot 37 but with slot 38 still covered, amplifier 43 is again operated to pull in relay 47, but timer 75 does not start charging its timing condenser because the contacts of relay 62 are still open. Because slot 38 is still covered, relays 49 and 62 are still deenergized and, as a consequence, the relays of timer 130 remain pulled in and those of timer 120 remain out. Also, relay 71 remains deenergized, hence belt 10 continues in motion.

Upon article 156 clearing slot 38, and with slot 37 also uncovered, amplifier 44 operates to pull in relay 49 which in turn pulls in relay 62. The effect of relays 49 and 62 being pulled in is to start charging the condensers of timers 75 and 130 and to start discharging the condenser of timer 120. Also, relay 71 is pulled in by the circuit: line wire 88, wire 155, wire 165, winding 72, wire 172, wire 166, contact 59, blade 57, wire 167, terminal 124, blade 133, terminal 125, wire 144, and wire 178 to line wire 87. This energizes solenoid windings 16 and 34, thereby lifting weighted wheel 15 and causing sealer and cutter 32 to cut and seal the edge of material 22 in back of article 156. This cutting and sealing operation continues for the time interval required for the negative charge on the timing condenser of timer 120 to diminish until its discharge device becomes conductive and pulls in its relays. This cut and seal for the rear edge of one package also constitutes normally, the cut and seal for the front edge of the next succeeding package. During this cutting and sealing operation, timer 130

drops out its relays as the negative charge builds up on its timing condenser and timer 75 continues with its relays dropped out.

If the next succeeding article 156 cuts the light passing through slot 37 before the prior article 156 has cleared the slot 38, no cut and seal will take place because, with amplifier 44 deenergized and relays 49 and 62 deenergized, the tube in timer 130 is still conducting and relay blade 137 is pulled into engagement with the contact of terminal 133, thereby opening one circuit that might be available for energizing relay 71; the other circuit for energizing said relay being opened by the deenergization of relays 49 and 62 resulting from slot 38 still being covered. If slot 38 is now uncovered and slot 37 is covered by a subsequent article 156, relays 49 and 62 are energized and relay 47 is deenergized. Also, blade 113 of timer 75, initially out, is pulled in a predetermined time after relay 47 is dropped out, as previously described, and blade 137 of timer 130, previously in, is dropped out upon the expiration of its timing period after the pulling in of relays 49 and 62. Also, blade 138 of timer 120, previously out, is pulled in upon the expiration of its timing period after the pulling in of relays 49 and 62. However, the pulling in of relays 49 and 62 completes a circuit previously traced through winding 72, relay 49 and timer 120, hence a cutting and sealing operation is performed for the duration of the timing cycle of timer 120. This completes the packaging of the article that just uncovered slot 38 and makes the first cut and seal for the package for the article covering slot 37, this latter cut and seal being closer than normal to said article. Although slot 37 was covered before 38 was uncovered, photocell 41 was unable to cause a cutting and sealing operation because the circuit for relay 71 controlled by relay 47 goes through timer 130 and this timer offers a closed circuit only after relay 62 has been pulled in for the timing period of timer 130, and relay 62 was not pulled in until slot 38 was uncovered.

Instead of the next succeeding package being spaced too near the prior article 156, assume that it is spaced slightly more than the desired distance, so that, just after a cut and seal operation is performed as slot 38 is uncovered, the extra spaced article cuts the light path through slot 37 and pulls in relay 47. The normal effect of this would be to immediately cause another cut and seal by a circuit previously traced but, because this circuit must go through the relay of timer 130 and as blade 137 of timer 130 is pulled in while a charge is building up on its timing condenser, this circuit cannot be completed until the condenser of timer 130 is charged and its discharge device rendered non-conductive, the charging starting at the time light is reestablished through slot 38. This timing period for the condenser of timer 130 is slightly longer than that of timer 120 and is adjusted so that the cellophane tube must move a distance sufficient to prevent a cut and seal that will overlap a previous cut and seal to thereby prevent damage to the cellophane by excess heat. Upon a sufficient time lapse to permit the condenser of timer 130 to charge up and render its discharge device non-conductive, so that switch blade 137 then engages its out contact connected to terminal 134, relay 71 can be energized by a circuit previously traced through relay 47 and timer 130 to cause another operation of the cutter and sealer, with the intervening piece of cellophane being wasted. Obviously, as the articles advance and are cut

15 and sealed to form individual packages, they slide off the end of table 38 into a suitable receptacle or chute 179.

20 In summary, as the articles advance along the conveyer, the first one to cut the light beam to photocell 41 causes a cutting and sealing operation and thereafter, if the articles are properly spaced, the reestablishment of a light beam through light 38 as the trailing edge of a package passes over that slot, causes a cutting and sealing operation which seals the back edge of one package and the front edge of another so that successive operations are under the control of the trailing edge of the packages passing over slot 38. In the event of articles being spaced too close, the trailing edge of the articles continues to govern the cutting and sealing operation and, if they be spaced too far apart, successive cutting and sealing operations will take place, one being governed by the trailing edge of a package and the other by the leading edge of the next package but timer 130, by its time delay or "memory" prevents one cutting and sealing operation following too soon after another.

Figure 2

The control components used in Figure 2 are essentially identical with those used in Figure 1 and a conveyer apparatus, not shown, is presumably the same as shown in Figure 1 with the exception that the distance of slot 37 to slot 29 is somewhat greater than in the previous example and is preferably adjustable. In other words, Figure 2 represents a modified arrangement of the control apparatus for the apparatus of Figure 1. Because the components are similar, they have been given similar numbers and the slight differences in the components involved will become apparent as this description proceeds. Because the present apparatus is essentially the same as to components, it is believed that a discussion of the operation of this apparatus will best show the relationship of the parts.

Assuming that an article 156 is approaching slot 37 but that, at this time, light from lamps 39 is shining through slots 37 and 38 on photocells 41 and 42 so that amplifiers 43 and 44 are both energized in a manner to pull in their respective relays. With relay 47 pulled in, relay 201 is also pulled in by the circuit: line wire 87, wire 202, wire 203, wire 204, wire 205, contact 53, blade 51, wire 206, winding 207 of relay 201, and wire 208 to line wire 88. With relay 201 pulled in, timer 75 has its control circuit completed, running from terminal 103 through wire 209, contact 210, blade 211, and wire 212 to terminal 107. With this control circuit completed, timer 75 has its timing condenser 98 charged; its discharge device 76 is non-conducting and its relays are dropped out so that switch blade 113 engages its out contact which is connected to terminal 117. At this same time, the control circuit for timer 130 is open hence the discharge device of this timer is conducting and switch blade 137 is pulled into engagement with the contact connected to terminal 133. Also, as relay 49 is pulled in, the control circuit between terminals 121 and 122 of timer 120 is open and relay blade 123 is pulled in.

When article 156 now moves into the path of light between lamp 39 and photocell 41 through slot 37 and cuts off this light, relay 47 is dropped out, thereby dropping out relay 201. Deenergizing relay 47 results in a cut and seal operation by the circuit: line wire 88, wire 214, wire 165, winding 72, wire 215, terminal 117 of timer 75,

switch blade 113 and terminal 118 of said timer, wire 216, switch blade 52, contact 54, wire 205, wire 204, wire 203, wire 202 and line wire 87. This energizes relay 71 and thus energizes the cutter and sealer 32 by the circuits: line wire 87, wire 202, wire 173, blade 73, contact 74, wire 174, solenoid winding 16, wire 175, solenoid winding 34, wire 176, wire 217 and line wire 88. As before recited, the energizing of solenoid winding 34 pulls armature 35 downwardly, thus driving cutter and sealer 32 downwardly to cut and seal the cellophane tube containing the articles being packaged. At this same time the deenergizing of relay 201 opens the afore-mentioned control circuit across terminals 103 and 107 of timer 75 thereby permitting the negative charge on the control grid of tube 76 to be dissipated. As this charge leaves, the control grid tends to become positive and the tube becomes conducting, whereupon timer 75 pulls in blade 113 into engagement with its "in" contact and out of engagement with the contact connected to 117. This breaks the control circuit for relay 71 and terminates the cut and seal operation. Simultaneously with this controlling action of timer 75, the control circuit of 130, from terminal 131 through wire 221, contact 222, switch blade 223 and wire 224 to terminal 132, is completed so that the timing condenser of this timer starts building up a negative charge and, upon this charge building up to a sufficient point to render its tube nonconductive, then it drops out blade 137 and opens the circuit between terminals 133 and 135.

Upon the termination of the afore-mentioned cut and seal operation the conveyor continues to advance the articles across table 28 as previously described and, upon an article 156 cutting the light path through slot 38, amplifier 44 operates to drop out relay 49 and this causes a closing of the control circuit for timer 120, running from terminal 121 through wire 226, contact 227, switch blade 57, wire 228 and terminal 122, so that the condenser of this timer may be charged negative and drop out blade 138 as its tube becomes nonconducting.

Upon article 156 clearing slot 37, amplifier 43 operates to pull in relay 47 and thus pulls in relay 201. This reestablishes the control circuit for timer 75 so that condenser 98 is again charged negative so that device 76 becomes nonconducting and drops out the timer relays. Also, the control circuit across terminals 131 and 132 of timer 130 is opened so that its condenser starts dissipating its negative charge to permit its tube to become conducting and pull in switch blade 137, as shown. As article 156 now clears slot 38, and reestablishes light to photocell 42, amplifier 44 operates to again pull in relay 49 which opens the control circuit for timer 120, thereby permitting its negative charge to be dissipated so that its tube is again rendered conductive whereby it can pull in switch blade 138. Upon timers 120 and 130 pulling in their relays, a second circuit for the cutter and sealer relay 71 is completed from line wire 88 by the circuit: wire 214, wire 165, winding 72, wire 231, switch blade 58, contact 60, wire 232, terminal 133, switch blade 137, terminal 135, wire 233, terminal 124, switch blade 138, terminal 125, wire 235, and wire 236 to line wire 87. It is noted that this circuit is completed only so long as the tube of timer 120 is still nonconducting and so long as the tube of timer 130 is conducting. If there is no subsequent package following 156 to cut off the light through slot 37, timer 130 remains conductive, hence the cir-

cuit through its relay contacts remain closed and, upon article 156 clearing slot 38, relay 71 is energized by the action of relay 49 pulling in and remains energized until timer 120 becomes conductive and pulls in its relay switch blade 138 to open the circuit above traced. However, a subsequent package 156 cutting the light through slot 37 would operate to drop out blade 137 of timer 130, as previously described, and thereby prevent photocell 42 from controlling the subsequent cut and seal operation. Slots 37 and 38 are preferably spaced so that a subsequent article cuts the path of light through slot 37 before light is restored through slot 38 by the prior article clearing said slot, hence photocell 41 normally controls the cutting and sealing operations and photocell 42 controls such operations when the spacing between the articles is excessive.

In this modification, the duration of the cut 20 and seal operations controlled by photocell 41 is controlled by timer 75 while the duration of the operations controlled by photocell 42 is controlled by timer 120. Timer 130 prevents photocell 42 from controlling the cutting and sealing when 25 photocell 41 is controlling because its delay period is sufficient to prevent it from ever pulling in its relays if the articles are properly spaced for, before one time period elapses, another starts.

The above disclosure shows two modifications 30 of the present control apparatus but one skilled in the art will see that many other substitutions and equivalents may be used and other obvious modifications come within the teachings of this disclosure, hence the scope of the invention 35 should be determined only by the appended claims.

I claim:

1. Control apparatus comprising a pair of circuit controlling pickup devices, a pair of amplifiers arranged to be individually controlled by each of said devices, a load relay, a plurality of relays controlled by said amplifiers, a plurality of time delay switches, a first electrical circuit for energizing said load relay including one of 45 said plurality of relays and a plurality of said time delay switches, a second electrical circuit for controlling said load relay including another of said plurality of relays and another of said time delay switches, circuit means for controlling 50 one of said time delay switches including said one relay, another electrical circuit including the other of said plurality of relays for controlling one of the time delay switches of said first electrical circuit, and a fourth circuit controlled by said other relay and controlling another of said time delay switches.

2. In a machine for packaging articles requiring an operation at each end of the article, said machine including means for moving said articles in spaced relation along a predetermined path, control apparatus for said machine including a relay for controlling said operations, a device operable in response to the presence of an article, apparatus controlled by said device for operating said relay, a second device spaced from said first device along said path and in the direction of motion of the articles through said machine, apparatus controlled by said second device for also operating said relay, and a timer controlled by one of said devices for preventing overlapping control of said relay by both of said devices.

3. Control apparatus comprising a pair of photocells arranged in spaced relation and each exposed to a source of light, the light for each 75 photocell being subject to sequential interruption,

11

an amplifier means controlled by each of said photocells, a relay means for each amplifier means arranged to be controlled by its respective amplifier means; another relay controlled by one of said amplifier controlled relay means, a load relay, a pair of timers, a circuit for controlling said load relay including one of said amplifier controlled relay means and one of said timers, and a second circuit for controlling said load relay including the other relay means and the other of said timers, said other relay also controlling said other timer.

4. For use with a packaging machine which feeds a continuous tube of transparent material having articles spaced therein past cutting and sealing means arranged to be intermittently operated for cutting and sealing the tube near each end of the articles therein to form separate packages for each article; control apparatus comprising first relay means for controlling said cutting and sealing means; a first circuit for energizing said relay means, said first circuit including a second relay, the normally closed contacts of a third timer and the normally closed contacts of a first timer; first photocell controlled means for controlling said second relay, said second relay also being connected in a control circuit for said first timer; a second circuit for controlling said first relay, said second circuit including a fourth relay and the normally closed contacts of a second timer; second photocell controlled means for controlling said fourth relay; and a fifth relay, said fourth relay also controlling said fifth relay; said fifth relay controlling said second and third timers and cooperating with said second relay for controlling said first timer.

5. In control apparatus having a load relay for controlling intermittent operations of a desired sort, a first device responsive to the presence of an object, electrical apparatus controlled by said device and including a timer for causing operation of said load relay for a predetermined period upon a response by said device, a second device spaced from said first device and also responsive to the presence of an object, additional electrical apparatus controlled by said second device and including a timer for causing operation of said load relay for a predetermined period upon said second device, and a third timer arranged to be controlled by one of said devices for controlling said load relay in a manner to insure a predetermined time period between successive operations of said relay.

6. In control apparatus having a load relay for controlling intermittent control operations, a first device operable in response to the presence of an object, apparatus controlled by said device for causing an operation of said load relay when said device determines the presence of such an object, a timer for determining the duration of the operations of said load relay, a second device operable in response to the presence of an object, and apparatus controlled by said second device connected to control the energization of said load relay in a manner to prevent operation of said relay by said first device when both of said devices are being operated.

7. Control apparatus comprising, a load relay, a pair of amplifiers each arranged to be controlled by an electrical pickup device, a relay controlled by one of said amplifiers, an electrical circuit including timing means arranged between said relay and said load relay, the other of said amplifiers controlling additional relay means, another electrical circuit including a second timer ar-

12

ranged between said additional relay means and said load relay, and a third electrical circuit including a third timer, said timer controlling at least a part of one of the above electrical circuits in a manner to require a predetermined time interval between operations of said load relay.

8. Control apparatus for a machine which sequentially performs operations on objects passing through said machine, said apparatus comprising a load relay means, a first electrical pickup device, electrical circuit means including a timer controlled by said first pickup device and arranged to control said relay means, said timer being arranged to control the duration of the operations of said relay means, a second electrical pickup device spaced from said first device in the direction of movement of said objects, additional electrical circuit means controlled by said second device and arranged to control said relay means, said additional circuit means being operative to prevent operation of said relay means by said first device when said second device is operative in a predetermined manner.

9. Sequentially operable control apparatus for controlling prescribed operations on objects passing through a machine comprising a principal switching means, a first electrical device responsive to the presence of an object, means including an electrical circuit connecting said device in control of said switching means, a second electrical device also arranged to respond to the presence of an object, means including a different electrical circuit for connecting said second device in control of said switching means, and timer means arranged to control the duration of the operations of said switching means.

10. Control apparatus for a machine which performs consecutive operations upon a series of articles passing through said machine in a predetermined direction, a relay for controlling said operations, a first photoelectric device responsive to the presence of an opaque article, electrical apparatus controlled by said device and arranged to control said relay, a timer arranged to control the time period of each operation of said relay, a second photoelectric device also responsive to the presence of an opaque article, said first and second devices being spaced apart in said predetermined direction by an amount based on the size of articles for which the machine is adjusted and apparatus controlled by said second device connected to said relay in a manner to prevent substantially simultaneous operation of said relay by both of said devices and to cause operation of said relay when either of said devices alone responds in an operative member.

11. In control apparatus for a machine of a sort performing consecutive operations in response to objects moving along a path, said operations being controllable by a relay, the combination comprising a relay, a first means capable of an output signal in response to the presence of an object, apparatus controlled by said first means for causing operation of the second named relay in response to an output signal from said first means, a second means capable of an output signal in response to the presence of an object, additional apparatus controlled by said second means for operating said second named relay in response to an output signal from said second means; and a timer controlled by one of said first and second means for insur-

ing a predetermined time interval between operations of said second named relay.

12. In a machine for performing operations upon objects moved along a predetermined path; a device disposed adjacent said path for performing said operations; a first means arranged in said path and responsive to a condition indicative of the presence of an object; apparatus controlled by said first means and including a timer, said apparatus being arranged to control said device for a period determined by said timer; a second means responsive to a condition indicative of the presence of an object, said second means being spaced along said path from the first means; additional apparatus including a second timer controlled by said second means, said additional apparatus also being arranged to control said device for periods depending on said second timer; and a third timer controlled by one of said first and second means for preventing overlapping control of said device by both of said means.

13. In control apparatus for a machine which performs intermittent operations, in combination, a machine controlling relay, a first means capable of an output signal in response to the presence of an object, electrical apparatus including a timer for causing operation of said relay for a predetermined time upon sensing an output signal from said means, a second means also capable of producing an output signal in response to the presence of an object, said second means being spaced from the first means in a direction such that it will normally be operated subsequently to said first means, additional 35 electrical apparatus controlled by said second means and including a timer for causing operation of said relay for a predetermined time due

to an output signal from said second means, and a third timer controlled by said second means for preventing operation of said relay by the first means for a predetermined period after the 5 relay is operated by the second means.

14. In a machine, means for performing operations upon objects movable through the machine, means for supplying objects to be worked on along a predetermined path, first electrical pickup means disposed in said path on one side of said operation performing means, means for connecting said pickup means in control of said operation performing means, second electrical pickup means arranged in said path on the other 10 side of said operation performing means, means connecting said second pickup means in controlling relation to said operation performing means, and time delay means controlled by one of said pickup means for insuring a predetermined time between subsequent operations of said operation performing means.

JERRY HAGEN.
